UNITED STATES PATENT OFFICE

CLEMMA R. RANEY, OF RIVERSIDE, ILLINOIS, ASSIGNOR TO INTERNATIONAL HARVESTER COMPANY, A CORPORATION OF NEW JERSEY

GRAIN BINDER

Application filed September 20, 1930. Serial No. 483,146.

This invention relates to grain binders. Grain binders as now standard in the art include a main frame carrying an accessory driving shaft inclined to the vertical, said shaft being appropriately supported in bearings mounted on the elevator frame that leads to the binder deck. This shaft carries a gear that is driven from another gear carried on the driving elevator roller shaft. In this fashion the vertically inclined shaft is driven and it, in turn, has other connections for driving the reel from its lower end and the butter mechanism on the binder deck from its upper end. The gear on this inclined shaft, which is driven from the elevator roller shaft, is subjected to a considerable load resulting in wear that eventually interferes with the proper driving of the related parts. Sometimes these driving and driven gears cannot properly be meshed because of variations in the manufacture of co-related parts. The problem, therefore, is to provide an adjustment in the form of a take-up device that will permit the proper meshing relationship between the driving gear on the elevator roller shaft and the driven gear on the inclined accessory shaft.

Accordingly, it is the primary object of this invention to provide a gear adjuster for the purposes stated, which will result in better operation of the driven accessory parts of the binder as well as permit of more accurate assembly, to compensate for variations in manufacture.

An embodiment of the invention has been selected by way of example as shown in the accompanying sheet of drawing, wherein:

Figure 1 is a general perspective view looking from the front of so much of the grain binder as is necessary to illustrate the invention and the co-related accessory driven parts;

Figure 2 is a sectional view through the inclined accessory shaft, showing its associated driving connections and the improved gear adjuster mechanism;

Figures 3 and 4 are respectively top and vertical sectional views of the gear adjuster spacer nut; and,

Figures 5 and 6 are respectively top and

elevational views of the adjusting spacer or quill.

So much of a grain binder main frame as is necessary for the purpose of this disclosure appears at 10, the same comprising a generally vertically disposed member, which carries at its upper end the conventional bracket 11 mounted above the elevator frame, not shown. This bracket 11 has connected to it in any appropriate manner a lower bearing 12 and an upper bearing 13, the two bearings mentioned serving as spaced supports for journaling an accessory shaft 14, inclined to the vertical, as shown in Figure 1. This accessory shaft at its upper end carries a bevel pinion 15 by means of an elongated keyway and key 16 to permit of slidingly moving the gear 15 axially of the shaft 14, as will later more fully appear.

The bevel gear 15 is driven from the bevel pinion 17 fixed to the front end of a roller drive shaft 18 that operates the elevator, not shown, which moves the grain to the binder deck, not shown, as is well understood in this art. Thus, the shaft 18 serves as a drive shaft and the accessory shaft 14 is driven therefrom.

The lower end of the shaft 14 carries a bevel gear 19, which drives a bevel pinion 20 on a shaft 21, which leads to and operates the reel, not shown, the shaft 21 being journaled in an extension of the bearing 12 heretofore described, which bearing 12 includes an upright bifurcated boss 22, which receives between its forks the lug 23 of a cup-shaped bearing block 24. As the bearing 12 is fixed, the lug and boss arrangement 22, 23 serves to hold the cup 24 against rotation in an obvious manner. This cup 24 receives the hub of a bevel gear 25, which drives the lower elevator by connections not necessary here to be shown. The important point to remember in this regard, however, is that the gear 25, by means of a pin 26, has a fixed position at all times on the shaft 14 and thus serves as a stop as will presently appear. The upper end of the shaft 14 carries connections, in the usual way, for driving a chain 27 that operates a butter mechanism 28 movable across the binder deck; not shown.

Due to the loads imparted to the bevel 15 as it takes the driving forces, considerable wear occurs on its teeth, which in time causes a loose driving connection between the gears 15 and 17 and, as a result, the accessory parts, such as the reel, the lower elevator, and the butter, are not properly driven. Accordingly, a cup-shaped adjuster nut 29, provided with a lower opening 30, is axially slid over the shaft 14 to rest on the upper edge of the hub of the gear 25. Said cup 29 at its upper edge is provided with an internally threaded opening 31 to receive a spacer quill or sleeve 32, which, at its upper end, abuts and serves as a support for the gear 15, while at its lower end said quill is threaded at 33, for a substantial distance along its lower length, threadedly to fit into the threaded opening 31 of the cup 29. The cup is furthermore provided with diametrically opposed pairs of vertically elongated slots 34 and 35, through which is passed a cotter pin 36, said pin also passing through an appropriate bore in the shaft 14. The upper end of the quill 32 is provided with an enlarged vertical slot 37 to provide a passage registering with the keyway of slot 16, so as not to interfere with the adjustment of the gear 15 and movement of the quill 32. Obviously now in practice, when wear results between the gears 17 and 15, the cotter pin 36 will be removed and, by means of a hand wrench engageable with a wrench portion 38 on the cup 29, said cup can be turned, threadedly to move the quill 32 upwardly to push the gear 15 into proper meshing engagement with the gear 17, whereby to take up play which has resulted from excessive wear. As a result, the shaft 14 and the accessories driven therefrom will be properly driven from the drive shaft 18. It will be understood that, in operation, the nut 29 and quill 32 turn with the shaft 14. After the adjustment has been effected, the cotter pin 36 is returned to either of the opposed slots 34 or 35, to lock the parts in their newly set position.

The gear adjuster mechanism just described also proves to be very useful in the factory assembly of the parts, because any variations resulting from manufacture can be compensated for by the means 29, 32 to cause the gears 15 and 17 to be properly set before the machine is shipped from the factory, to insure correct meshing relationship.

From this disclosure, it will be apparent that an improved gear adjuster has been provided for the accessory drive shaft of a grain binder, which is simple, cheap to produce, and effective in operation, and that such structure accomplishes the objects heretofore recited.

It is the intention to cover any such changes and modifications of the example herein chosen for purposes of illustration which do not depart from the spirit and scope of the invention as expressed in the appended claims.

What is claimed is:

1. In a grain binder, a drive shaft carrying a drive gear, an accessory driven shaft carrying a driven gear mounted for axial sliding movement on the shaft and in mesh with the drive gear, a stop member spaced from the driven gear and having a fixed location on the accessory shaft, and a spacer sleeve between the stop and sliding gear compressing two telescopic parts threadedly interfitted and adapted to slide said sliding gear on its shaft to take up wear between the driving and driven gears. 70

2. In combination, a drive shaft carrying a driving gear, a driven shaft carrying for axial sliding movement a meshing driven gear, a stop member on the driven shaft spaced from said gear thereon, a nut device abutting the stop member and surrounding the shaft for turning movement thereon, and a quill threaded into the nut device and abutting the driven gear. 80

3. In combination, a drive shaft carrying a driving gear, a driven shaft carrying for axial sliding movement a meshing driven gear, a stop member on the driven shaft spaced from said gear thereon, a nut device abutting the stop member and surrounding the shaft for turning movement thereon, a quill threaded into the nut device and abutting the driven gear, and releasable means 90 for locking the nut against turning movement. 95

4. In combination, a drive shaft carrying a driving gear, a driven shaft carrying for axial sliding movement a meshing driven gear, a stop member on the driven shaft spaced from said gear thereon, a nut device abutting the stop member and surrounding the shaft for turning movement thereon, a quill threaded into the nut device and abutting the driven gear, said nut being provided with opposite slots in registry with a bore through the driven shaft, and a removable pin passed through said slots and bore to prevent turning of the nut device. 100 105 110

5. In combination, a drive shaft carrying a driving gear, a driven shaft inclined to the vertical carrying for axial sliding movement a meshing driven gear, a stop member on the driven shaft spaced below said gear thereon, a nut device resting on the stop member and surrounding the shaft for turning movement thereon, and a quill threaded into the nut device and abutting the driven gear. 115

In testimony whereof I affix my signature. 120

CERTIFICATE OF CORRECTION.

Patent No. 1,880,483.

October 4, 1932.

CLEMMA R. RANEY.

It is hereby certified that error appears in the printed specification of the above numbered patent requiring correction as follows: Page 2, lines 73 and 74, claim 1, for the word "compressing" read comprising; and that the said Letters Patent should be read with this correction therein that the same may conform to the record of the case in the Patent Office.

Signed and sealed this 29th day of November, A. D. 1932.

(Seal)

M. J. Moore,
Acting Commissioner of Patents.
